GRAVITY FILLING MACHINE WITH PNEUMATICALLY DISCHARGE CONTROLLING CUTOFF

William E. Gross, Joppa, Md.

Application June 9, 1949, Serial No. 98,121

2 Claims. (Cl. 226—97)

(Granted under the act of March 3, 1883, as amended April 30, 1928; 370 O. G. 757)

1

The invention described herein may be manufactured or used by or for the Government for governmental purposes without payment to me of any royalty thereon.

This invention relates to filling receptacles, more particularly to novel apparatus for automatically filling gas mask canisters of the radial flow type.

The primary object of the present invention is to provide a machine that will automatically deliver to a plurality of receptacles a charge of granular material, while maintaining uniform bulk density of the charge delivered to each receptacle.

A supplementary object is to provide such a machine that will deposit an annular uniform load of material into each of a plurality of receptacles wherein each receptacle has a central, longitudinal member free at its upper end prior to the filling operation.

A further object is to provide such a machine that will maintain the inner and outer members of a radial flow canister in centered relationship with each other and with the filling tube during the filling operation.

Additional objects will more plainly appear from the detailed specification and drawings herein presented in exemplification but not in limitation of the present invention. Like reference characters represent like parts in the accompanying drawings which diagrammatically illustrate a preferred embodiment of the present invention and wherein:

Fig. 1 represents a front elevation of the assembled machine.

Fig. 2 is a front elevation, partly in cross-section, of one of the filling tubes.

Fig. 3 is a plan view of the lower chuck table.

Fig. 4 is a plan view of the upper hopper table.

Fig. 5 is a vertical cross-sectional view of the canister chuck.

Fig. 6 is a vertical cross-sectional view of the canister centering holder.

Fig. 7 is a plan view of the centering holder.

Fig. 8 is a vertical cross-sectional view of the automatic measuring apparatus.

Fig. 9 is a vertical cross-sectional view of the adjusting means for the cylindrical measuring tube, taken on line 9—9 in Fig. 8.

Fig. 10 is a plan view of the upper measuring plate.

Fig. 11 is a plan view of the lower measuring plate.

Fig. 12 is a diagram of a preferred pneumatic control system for the measuring apparatus.

2

Fig. 13 is a plan view of the chuck plate shown in Fig. 5.

Fig. 14 is a vertical cross-sectional view of the outer wall member and center tube member of a canister of the radial flow type, prior to the filling operation.

It is essential that a radial flow canister for gas masks be filled in a manner that meets the following requirement, in order that the charge will not become channeled and consequently inoperative or hazardous when used. Among these requirements are:

The charge must be of uniform bulk density. As used herein, bulk density is determined as follows:

$$\text{Bulk density} = \frac{\text{weight of sample}}{\text{volume of sample}}$$

20 The various sizes of the particles must be uniformly distributed within the charge.

The central tube of the canister must be kept in accurately centered relationship with the outer walls of the canister. This is essential to maintain uniformity of load and to insure the subsequent accurate assembly of the gas mask canister and its top.

25 The feeding of mixed-sized granular particles has been described in U. S. Patent No. 2,332,512, issued October 26, 1943, jointly to John C. Goshorn and the applicant. The present application is an improvement on the apparatus described therein, that provides a novel automatic filling machine, and, in addition to other improvements, provides novel means for maintaining a uniform charge in radial flow canisters.

30 In general, as shown in Fig. 1, the assembled machine comprises horizontal base 20; vertical supports 21; horizontal top support 22; and horizontal cam support 49. Vertical rotating shaft 23 is mounted in roller bearing 24 on the base 20 and roller bearing 25 on top support 22. Mounted on base 20 is motor drive assembly 30 which drives shaft 23, through pinion 26, and gear 27 which is attached to shaft 23. Fixed to shaft 23, 35 for rotation therewith, is chuck table 28, shown in Fig. 3, and hopper table 29, shown in Fig. 4.

The motor drive assembly 30 includes a source of electric current, indicated at 32, and a conduit 31 to motor 33, which drives, through belt 34, a well known variable pitch pulley unit at 35. The pivoted tilting arm 36 is adjusted by handle 37 on adjustable nut unit at 38. Drive pulley 39, through belt 90, drives driven pulley 91 on shaft 92 in reducing gear unit 93. Unit 93 drives turntable driving pinion 26, held on shaft 94 by hub 55

attachment 95. Pinion 26 drives turntable driven gear 27, which is fixed to the vertical main shaft 23 by hub attachment means at 96.

Cam ring 40 is fixed to support 49, positioned below chuck table 28, and is arranged so that shaft 23 rotates within ring 40. Cam ring 40 includes the depressed track portion 41 shown in Fig. 1, positioned at the canister loading and unloading stations of table 28.

Attached to the under side of chuck table 28 is chuck bracket 42, as shown in Fig. 5, arranged to slidably engage the L-shaped chuck arm 43 which is mounted for slidable vertical movement within the two opposite vertical plates of chuck bracket 42. Mounted on chuck arm 43 is chuck roller 44, arranged for rotation on its shaft 45, and arranged so that chuck arm 43 rides on roller 44 as it travels on cam ring 40. Mounted on the upper horizontal face of chuck arm 43 is chuck plate 46, apertured at 47 to receive the central tube 61 of canister 60, as shown in Fig. 13.

Attached to the under side of table 28 and positioned in alignment with chuck plate 46 is chuck guide assembly 50, shown in Figs. 6 and 7. This assembly comprises plate 51, provided on its under side with recess 52, adapted to receive the top 64 of canister tube 61. Positioned adjacent to recess 52 are radial guide shoulders 53 and feed apertures 58. Removably attachable to plate 51 is annular adaptor 54, which includes the downwardly projecting annular members 55 and shoulder portions 56. Adaptor 54 is readily fitted to plate 51 by means of bolts 57, and may be removed and replaced by other adaptors suitable for various canister or receptacle shapes and dimensions.

Fixed to the top side of chuck table 28 is the upwardly projecting annular tube holder 70, arranged to releasably position the lower ends of tubes 71 on chuck table 28. Attached to the under side of hopper table 29 is downwardly projecting upper tube guide 72, adapted to slidably and releasably engage the upper portion 79 of tubes 71. Apertures 73 in hopper table 29 are arranged to be centered with the vertical axis of tubes 71 and funnels 74.

As shown in Fig. 2, filling tubes 71 preferably include for accessibility a telescoping top tube portion 79, lockable by means of pin 97 and bayonet slot 98. Positioned in the top of tube portion 79 are the spaced apart, horizontally mounted screen members 63, as described in the aforementioned U. S. Patent No. 2,832,512.

Positioned for operating registration with funnels 74 is automatic feed metering assembly 80 (see Fig. 8), comprising upper measuring plate 81, lower feed plate 82, both mounted for limited rotation on shaft 83 mounted on top support 22. Also mounted on top support 22 is feed hopper 84 and its measuring cylinder 85. The feed hopper 84 is positioned above the aperture sector of measuring plate 81, and the measuring cylinder 85 is positioned between the apertured sectors of plates 81 and 82 so that hopper 84, cylinder 85, funnels 74, and aperture 73 may all be brought into operating registration with tubes 71. Measuring cylinder 85 is provided with adjustable wall 86, slidably mounted for horizontal adjustment inwardly and outwardly by means of adjusting apparatus 87, so that the volume of cylinder 85 may be adjustably fixed within pre-determined limits. Upper measuring plate 81 is provided with circular aperture 88, and lower feed plate 82 is provided with similar aperture 89; so positioned that when upper aperture

88 is in registration with hopper 84, lower aperture 89 will be out of registration therewith and when lower aperture 89 is in registration with the lower portion of measuring tube 85, upper aperture 88 will be out of registration therewith. Reciprocating motion is provided to plates 81 and 82 by pneumatic means subsequently described.

Attached to the periphery of hopper table 29, as shown in Fig. 1, are valve actuating rollers 75, rotatably mounted on shafts 76 and positioned to engage the arm 77 of valve assembly 78, as shown in Fig. 12.

Valve assembly 78, as shown in Fig. 12, comprises a pivoted spring-pressed valve actuating mechanism or arm 77, positioned in the path of actuating rollers 75 on the periphery of rotating hopper table 29. Arm 77 actuates a standard four-way, two-position pneumatic valve of a type well known in the art, as indicated at 78 in Fig. 12. Valve 78 is provided with an intake line 105 and exhaust line 106. Conduits 107 and 108 are connected by leads 109 and 110 to valve 78, and to each end of pneumatic cylinders 100 and 101, as shown in Fig. 12. Cylinder 100 is provided with reciprocating piston 102 connected to hopper plate 82 by means of operating linkage 104, and is arranged to provide plates 81 and 82 with concurrent reciprocating motion, so that when aperture 88 is in registration with cylinder 85, aperture 89 will be out of registration therewith, and vice versa.

Pneumatic cylinder 101 is provided with reciprocating piston 103 and is positioned below chuck table 28, as represented in Figs. 12 and 3, so that in operation the forward movement of piston 103 will contact the empty canister 60 and advance it into its loading position on chuck plate 46, as shown in Fig. 3.

The valve system shown in Fig. 12 is synchronized to operate in the following manner: when chuck plate 46 is in its lowered position for engaging empty canister 60, as shown in Fig. 3, the piston 103 pushes canister 60 into engagement with chuck plate 46, and as canister 60 is engaged, by the travel of the chuck out of the depressed portion 41 and onto the elevated portion 40, the piston 102 reciprocates plates 81 and 82 on shaft 83, so that apertures 88 and 89 are in their loading positions. This means that aperture 88 is then in registration with cylinder 85, and aperture 89 is out of registration with cylinder 85. As the table 29 continues its rotation, the roller 75 disengages the actuating arm 77, the tension on its spring returns the arm and the valve to its disengaged position and the above described action of the pistons 102 and 103 is reversed. As each succeeding roller moves into and out of contact with the arm 77 the entire operation is repeated; each aperture being pivotally first moved one way and then the other way with respect to the cylinder 85.

In actual operation, each filled canister 60 is discharged at chute 111, as shown in Fig. 3, currently with the engagement of empty canister 60 with chuck plate 46. As each of the tubes 71 and funnels 74 travels on rotating table 29 into registration with cylinder 85, the reciprocation of piston 102 dumps the charge of material from cylinder 85 into the funnels 74 during the time each tube 71 travels through its registration position therewith. At the moment that the travel of table 29 has completed the registration of funnel 74 with hopper 84, piston 102 concurrently actuates plates 81 and 82 so

that cylinder 85 is closed at the bottom and opened at the top, through which it receives by gravity a new charge of material from hopper 84. This charge is leveled off within cylinder 85 by the return motion of plate 81, thus metering the charge in cylinder 85. This charge is subsequently delivered to the oncoming tube 71 in the manner already described. This provides a volumetric accuracy within plus or minus $\frac{1}{2}$ of 1% as measured on the volume meter described in aforementioned U. S. Patent No. 2,332,512.

In actual practice, a preferred machine may embody a continuous series of 30 or more tubes, although, for clarity, only 6 are indicated in the drawings herewith. The preferred rate of rotation for tables 28 and 29 is approximately 2 per minute, in a counter-clockwise direction. A preferred form of receptacle suitable for filling by the apparatus of the present invention is shown in Fig. 14, which represents portions of a radial flow canister 60, such as is used for military gas masks. The canister 60, as shown in Fig. 14, comprises a base 62, a central tube member 61 and a tube cap 64. The tube 61 is loosely held by the base 62 prior to receiving the annular charge of granular material, for example, sorbents or mixtures thereof, after tube 61 has been accurately centered by the chuck mechanism 50 of the present invention, as previously described herein. A production of 3600 filled canisters per hour has been obtained under factory conditions by the apparatus of the present invention.

Operation

For a machine including thirty of the tubes 71, the motor drive 30 is adjusted by handle 37 and gear box 93, in a manner well known in the art, so that shaft 23 and tables 28 and 29 rotate, preferably in a counter-clockwise direction, at about 2 R. P. M. When counter-clockwise direction is used, the chuck loading station adjacent piston 103 in Fig. 3 is positioned in advance or to the right of the receptacle discharge station adjacent the chute 111. If clockwise rotation is used, the positions of these two stations are, of course, reversed with respect to the direction of travel.

After the proper speed is set, the proper adaptor plate 54, as shown in Fig. 6, may be attached by bolts 57 to guide plate 51 in chuck guide unit 50. The adaptor plate 54 is chosen so that its shoulders 55 and recess area 56 will conform to the wall and tube formation of the receptacle 60 to be filled. Cylinder 85 is next adjusted to measure the desired volume of the charge by setting wall 86 by means of adjusting mechanism 87, as shown in Fig. 9.

Next, current is applied from source 32, motor drive 30, and gear 27 to shaft 23 and tables 28 and 29. Chucks 50, tubes 71, and funnels 74 all travel with tables 28 and 29 in a continuous path into and out of successive registration with cylinder 85, loading station 112, and discharge station 113, as shown in Fig. 3. As the chuck roller 45 travels on cam ring 40 into the depressed track portion 41, chuck arm 43 slides downwardly in bracket 42 and thereby lowers chuck plate 46 into its receiving position.

At this moment valve actuating rollers 75 actuate valve arm 77, which causes piston 103 to push empty receptacle 60 onto chuck plate 46 which is then elevated by the travel of roller 45 out of the depression 41 and back onto the elevated cam ring 40. This upward movement of

plate 46 forces the upper edges of the receptacle into the shoulder recessed area 56 in guide unit 50, and also guides the tube 61 into the recess 52, so that cap 64 and tube 61 are centered therein with respect to the receptacle 60 and chuck unit 50 and chuck plate 46. At this time the lower end of tube 61 projects downwardly, as shown in Fig. 5, through aperture 47 in plate 46, and the base 62 is held in position under the arms of plate 46, as shown in Fig. 13.

Subsequently, as tube 71 travels into registration with cylinder 85, the roller 75 disengages the spring-pressed arm 77, the arm, by reason of the compression of its spring reverses valve 15 78 in the synchronization previously described. For example: as chuck arm 43 goes into its upper position, as it leaves loading station 112, piston 103 goes into its retracted position, lower feed plate 82 goes into its open position, and upper feed plate 81 goes into its closed position. When roller 75 disengages the arm 77 the compression of its spring is released and pistons 100 and 101 are again actuated by valve 78. This causes piston 103 to advance and push the next 20 empty receptacle arriving at station 112 onto plate 46. It also causes piston 102 to reciprocate plates 81 and 82, so that lower plate 82 is in its closed position at cylinder 85 and upper plate 81 is in its open position to receive material from hopper 84. When lower plate 82 is in its open position, the accurately metered material drops from cylinder 85 through aperture 89, funnel 74, hole 73, screens 63, tube 71, apertures 58, around tube 61, and into receptacle 60.

35 Funnels 74 preferably may be made elliptical in horizontal cross section, so that they will remain in registration with cylinder 85 until each entire charge of material is received in each of funnels 74.

40 After the annular metered charge of granular material has filled receptacle 60, chuck arm 43 travels into the depressed portion 41 of cam ring 40. This lowers plate 46, releases receptacle 60 from guide unit 50, and as plate 46 continues 45 its travel with table 28, chute arm 114 engages filled receptacle 60 and it is moved away, preferably by a conveyor belt of the type well known in the art. In this manner station 112 receives a continuing series of empty receptacles, continuously metered at cylinder 85, continuously filled at hopper unit 80, and continuously discharged accurately and uniformly filled at station 113 at the rate of 1 per second.

55 The foregoing drawings and specification illustrate one preferred embodiment of the present invention which is not intended to be limited thereto, but contemplates all embodiments and modifications within the spirit and scope of the appended claims.

I claim:

60 1. Automatic apparatus for successively depositing charges of granular material in a plurality of receptacles revolving about a common center, each of said receptacles having an outer circular wall surrounding an inner longitudinal member having an upper end portion and a base provided with a central aperture, said longitudinal member being inserted in said aperture and being free for limited movement at said upper end portion prior to the depositing operation of said apparatus; a series of vertical filling tubes 65 each of which revolves about said common center and is arranged to provide for the free fall of said material into one of said receptacles from a substantial altitude, a metering means for uniformly delivering a predetermined amount of

said material to each of said tubes; a hopper means for the delivery of said material into said metering means, a series of chucks each of which is arranged to guide and hold one of said receptacles in such a manner that said longitudinal member is in centered relationship with said wall and in the aperture of said base during said depositing operation; a receiving station for engaging said receptacles in said chucks; a delivery station for discharging said receptacles from said chucks; a pneumatically operated piston and link assembly having two pistons, one of which is arranged to be moved forward and backward and in sequence to open and close said metering means; a valve for reversing the movement of said assembly, a pivotally mounted actuating arm for reversibly actuating said valve; a roller mounted adjacent to the outer periphery of each of said tubes and arranged to move with its adjacent tube and into and out of contact with said arm in a manner whereby said piston assembly will be moved into one operating position when the roller is out of contact with said arm; the other of said pistons being operatively connected to said valve and arranged to move said receptacles into engagement of said chucks and means arranged to provide concurrent operation of each of said pistons by said valve.

2. Automatic apparatus for depositing granular material into each of a plurality of receptacles of the type including an outer wall, a centrally apertured base portion, and an inner longitudinal member in said apertured base portion, said apparatus comprising a metering means, a series of elongated vertical filling tubes arranged to revolve about a common center and adapted to receive said material from said metering means and discharge said material into said receptacles, and to provide a free fall of said material into said receptacles from a substantial altitude, a hopper means adapted for delivery of said material into said metering means, a series of chucks

5 below and spaced apart from said tubes for holding said receptacles, and arranged to guide and hold the inner longitudinal members of said receptacles in centered relationship with their outer walls, stations for the engagement and discharge of said receptacles by said chucks, and means for causing travel of said tubes and said chucks into and out of vertical alignment with said stations; said metering means being actuated by said travel for measuring and dropping a uniform quantity of said material through each of said tubes and into said receptacles, said travel being accomplished by pneumatic means including a pneumatically operated piston and link assembly operatively coupled to said metering means and said chucks and arranged to open and close said metering means; a valve for reversing the movement of said piston and link assembly; a pivoted actuating arm for operating said valve; and a roller mounted adjacent to the outer periphery of each of said tubes in a manner whereby each roller is arranged to move into and out of engagement with said pivoted actuating arm in a manner whereby said valve reversibly actuates said metering means each time one of said rollers moves into and each time one of said rollers moves out of engagement with said actuating arm.

30 WILLIAM E. GROSS.
